L. G. NICOLL

DECORATED OR ORNAMENTAL WOODWORK AND OTHER STRUCTURAL MATERIALS

Filed Sept. 6, 1924

L. G. Nicoll,
By Marks Clark

Attorney

UNITED STATES PATENT OFFICE.

LEONARD GEORGE NICOLL, OF LONDON, ENGLAND.

DECORATED OR ORNAMENTAL WOODWORK AND OTHER STRUCTURAL MATERIALS.

Application filed September 6, 1924. Serial No. 736,351.

To all whom it may concern:

Be it known that I, LEONARD GEORGE NICOLL, a subject of the King of Great Britain and Ireland, and residing at 5 Tetherdown, Muswell Hill, London, N. 10. England, have invented certain new and useful Improvements in and Relating to Decorated or Ornamental Woodwork and Other Structural Materials, of which the following is a specification.

This invention relates to decorated or ornamental woodwork as, for instance, cabinet work and decorative or ornamental wood fitting, and other structural materials.

15 As is well known, in order to impart or heighten the decorative effect of woodwork it is customary to treat the exposed surfaces in one or other of a variety of ways, one of the commonest being that of veneering 20 with a thin layer of material—usually wood—of a more ornamental character. In some cases the veneer is of the same variety of wood as is the base, differing therefrom merely in the character of the grain, but 25 more usually the base is of a cheap or common wood while the veneer is a thin layer of a wood of a more costly kind.

A number of cheaper methods of decorating wood surfaces so as to produce thereon 30 a representation of a more expensive or decorative wood are also known. For instance, it has been proposed to subject a wood surface to a printing and indenting operation by means of engraved rollers or 35 to transfer a printed design imitating the grain of wood to a suitable surface by applying thereto a paper on which a reverse design is printed in colors, capable of being softened by moisture.

40 The present invention consists broadly in a new article of manufacture, namely structural material having in substantially immediate or direct and permanent contact with one or more of its surfaces a photographic image of the grain or veining of a 45 naturally occurring material such as wood or stone formed with the aid of a photographic negative of such grain.

As instances of what is intended to be 50 included within the scope of the term "structural material" as used herein the following materials are specified as examples:—sheet metal, pulp board, natural or artificial stone including slate and artificial slate as, for instance, the so-called asbestos slate.

With advantage the photographic image is one formed in a silver salt emulsion.

Preferably, the wood or other structural material has in substantially immediate or 60 direct and permanent contact with one or more of its surfaces a transferred photographic image of the grain of another wood.

The invention will be described further and by way of example with reference to 65 the accompanying drawings, in which:—

Figure 1 represents a photograph of a section of wood having a suitable grain. This figure is a positive of the grain, while

Figure 2 is a similar view representing 70 a negative of the grain.

Figure 3 is a section of the photographic prints, positive or negative, as shown in Figures 1 and 2.

Figure 4 is a section showing a layer of 75 three-ply wood with the photographic image in direct or immediate contact with one surface of the wood and the paper backing in process of being stripped off.

Figure 5 is a view showing positives and 80 negatives of the grain of wood, the positives being located at the top right-hand and bottom left-hand corners, while the negatives are located at the left-hand top and right-hand bottom corners.

Figure 6 is a section of the wood thus 85 treated.

In the drawings, 1 represents the image formed in a light sensitive silver salt emulsion; 2 represents the paper backing on 90 which this image is produced; 3, in Figure 4, represents a sheet of three-ply wood with the photographic image 1 in direct or immediate contact with it, the said photographic image being transferred to the 95 three-ply wood by rolling or otherwise forcing the photographic print of the grain of the wood produced upon a suitable stripping bromide paper and then stripping off the paper support for the image.

In Figures 5 and 6 positive and negative 100 representations of the grain of a piece of wood veneer are so laid up as to resemble quartering and to give the light and shade effect which is presented by certain woods, such as mahogany.

In Figure 6, 4 represents the wood or the like forming the base or support for the image, while, as in the previous figures, 1 110 represents the photographic image.

In accordance with the invention, the surface may be constituted by a photographic

image of the grain or veining of a single variety of wood or other naturally occurring material, such as marble, or of a plurality of varieties in which case the surface will represent 5 inlay or marquetry work and in such case also the surface may comprise an image or images of the materials, for instance pearl, ivory, bone or tortoise shell, not infrequently employed in forming such work.

10 The production of the print in the silver salt emulsion may be effected in any suitable manner; for instance, the print may be produced on a temporary support and then transferred to the surface of the wood to 15 be treated.

To this end, a bromide paper adapted to permit the image produced thereon to be transferred to another supporting surface may be used.

20 The print may, if desired, be toned as a whole or locally or redeveloped or otherwise treated to impart to it the desired colour or intensity.

It might appear that a photographic print 25 suitable for transfer to the surface to be decorated could normally be formed by the employment of a negative obtained by exposing in the customary manner a suitably sensitized plate in a camera to secure a 30 negative of the grain of the wood or veining of a stone, the image of which it is desired to reproduce. In practice it is found, however, that such negatives or positives which are correct or true prints of such 35 negatives are in many cases not wholly suitable. Further, in use these negatives or true positives are liable to become injured.

Preferably, therefore, corrected or adjusted negatives or positives are produced 40 by forming a bromide print by the projection of light through a negative obtained by exposure in a camera or a positive formed from such a negative on to a sheet of "bromide paper" adapted to permit the 45 paper support to be stripped from the emulsion, while locally controlling the exposure of the bromide paper, and transferring the emulsion after development and fixation to a sheet of transparent material 50 such as glass. By this means a transparency is obtained which may be used without any special skill on the part of the operative in making the prints which are subsequently transferred to the surface to be decorated.

55 These prints will be contact prints formed on a suitable bromide paper and they will be transferred to the material to be decorated.

Prior to effecting the transfer of the 60 image the surface of the structural material may be treated with an adhesive which may be of a non-aqueous character, for instance an alcoholic solution of shellac.

When the image has been produced on the 65 original surface of the wood or other struc-

tural material which, if desirable or necessary, may have been treated or not with a wood filler or other material adapted to close the grain or impart to it a suitable surface as, for instance, by modifying its original colour, the new or modified surface thus produced may be further treated as, for instance, by staining, varnishing or polishing.

When it is desired to provide on the surface a photographic image of which individual portions are counterparts or are the mirror images of others, as would be the case in producing a representation of a panel veneered in two sections, for instance, with two pieces of veneer of substantially the same grain, the one being reversed relatively to the other, two prints may be formed, one in the usual way, the other with the negative reversed.

85 The following particulars are given, by way of example, to illustrate a suitable method of carrying the invention into effect:—

90 A photographic negative of a decorative wood surface such, for instance, as a marquetry panel is taken, a panchromatic plate or film being employed in conjunction with a light filter adapted to produce an accentuated or forced representation of the grain, and from the negative a print on transfer bromide paper is made.

95 The print is toned by the well known "ferricyanide-sodium sulphide" method or by the "copper" toning process wholly or locally depending upon the effect it is desired to secure, or the character of the marquetry panel.

100 To the surface of a panel of wood, finished by sanding, an adhesive of the consistency of cream and comprising gelatine and glue is applied hot and the face of the toned print is, after hardening in one of the usual baths, likewise treated with the adhesive and the coated surfaces of the wood panel and of the print brought together and squeegeed into firm contact, the panel with the print secured to it being placed under pressure until the adhesive has hardened and the paper backing or support may be readily stripped off.

105 The wood panel with the print from which the backing has been stripped is then rubbed over with a solution of wax and French polished or varnished.

110 In carrying the invention into effect with a view to the decoration of metal or stone or artificial stone, to the surface of the material, after treatment if necessary, to reduce its porosity or provide a suitably smooth surface, a photographic print of the grain of a wood or stone formed by exposing a sheet of a bromide paper of the known character which is adapted to permit the paper being stripped from the colloid 115

layer including the light sensitive silver salt, is applied with the printed surface downwards or in contact with the material while wet. The print is rolled or pressed into firm contact with the material and subjected to such further treatment as may be necessary to enable the paper support of the print to be stripped or separated from the colloid layer. Thus, for instance, after firmly 10 squeegeeing or pressing the surface of the print into contact with the surface of the material to be decorated a jet of steam may be applied to the paper backing in order to soften the gelatine or to melt the waxy 15 material which is interposed between the emulsion and the paper backing, and when the connection between the colloid layer in which the print is formed and the paper has been suitably weakened the paper is gradually peeled or stripped off, leaving the print 20 firmly secured to the structural material.

When the print is thoroughly dry the surface may be treated by lacquering, polishing or enamelling.

25 In some cases it may be desirable to apply to the structural material an adhesive adapted to secure firm contact between the print and the surface, but as a rule this is unnecessary. Dependent upon the character 30 of the wood or stone which the material treated is desired to simulate, the surface of the material may be tinted prior to applying the print. Thus, if the surface is normally dark, it may be furnished with a coat of 35 paint or priming material of a light colour which may, in general, correspond with the natural colour of the wood or stone, the grain or veining of which is to be reproduced on the said surface. Similarly, the 40 print may be toned or transparent colouring materials may be applied to the surface after the print has been transferred thereto provided, of course, that the surface of the material is naturally light in colour or has

been made suitably light in colour by the 45 application thereto of suitable pigments.

The invention is particularly applicable to the treatment of sheet metal such as is now used in the manufacture of furniture and to the treatment of the so-called asbestos slate. Natural slate treated in accordance with the invention is particularly adapted for use in forming mantelpieces. 50

It is to be understood that the mere connection with the surface of a body of structural material of a photographic image with an opaque support, such as paper, intervening between it and the surface of the structural material is expressly excluded from the scope of the present invention. 55

Having now described my invention, what I claim as new and desire to secure by Letters Patent is:—

1. The process of producing decorated structural material which comprises forming a photographic negative of the grain of a naturally occurring material by exposing in a camera a sensitized surface adapted to yield a transparency, forming by projection with the aid of said negative a print 70 on paper coated with a "bromide" emulsion, transferring the exposed bromide emulsion to a sheet of transparent material and using the resulting transparency in forming a contact print in a light sensitive silver salt 75 emulsion on a temporary support and transferring the print to a surface of the structural material to be decorated.

2. A new article of manufacture, namely structural material, having in immediate 80 and permanent contact with one of its surfaces an emulsion containing diagonally opposed negative and diagonally opposed positive silver images of the grain of a naturally occurring material. 85

In testimony whereof I have signed my name to this specification.

LEONARD GEORGE NICOLL.
